BRUSH HOLDER

Filed Sept. 10, 1937

UNITED STATES PATENT OFFICE

2,171,920

BRUSH HOLDER

Winfred W. Dorsey, Mount Vernon, Ohio

Application September 10, 1937, Serial No. 163,314

1 Claim. (Cl. 248—360)

This invention relates to an improved brush holder.

One object of the invention is to provide a brush holder which is adapted to be mounted on a paint brush or the like and which will effectively support the brush in a position convenient for manual engagement when the brush is not being actually used.

Another object of the invention is to provide a brush holder which will be formed from a single strand of wire and which will be securely fastened to the body of the brush in such a manner that the brush, when supported by the holder, will be prevented from wobbling from side to side.

15 A further object of the invention is to provide a brush holder which will be extremely simple in construction and durable in use so that it will be able to withstand the rigors of hard usage.

20 And the invention seeks as a still further object to provide a brush holder which will be mounted in the body of the brush in such a manner that reinforcement for the holder and brush will be provided and liability of accidental displacement of the brush holder from the brush obviated.

25 Other and incidental objects will suggest themselves during the course of the following description.

Referring to the drawing forming a part of my application:

Figure 1 is a side elevation of my improved brush holder as it would appear supporting a brush on a paint pot or the like.

Figure 2 is a detail perspective view showing my improved brush holder as it would appear ready for use.

Figure 3 is a horizontal sectional view on the line 3—3 of Figure 1, looking in the direction indicated by the arrows.

40 Figure 4 is a perspective view showing a single strand of wire as it would appear before being twisted and bent into shape to define my improved brush holder.

Figure 5 is a detail plan view showing a slightly modified form of the invention.

Referring now more particularly to the accompanying drawing, wherein like numerals of reference designate like parts throughout the various views, the numeral 1 indicates in general a brush which is of the type ordinarily used for painting or like work. The brush 1 includes a body 2 and a handle 3. A tuft of bristles is shown at 4 and the tuft is held in place on the body 2 by means of a ferrule 5.

55 As best seen in Figures 2 and 3 of the drawing,

the body 2 of the brush is formed, medially of its width and immediately above the ferrule 5, with a pair of parallel openings 6 and 7 which extend transversely through the body throughout its thickness.

5 My improved brush holder is shown generally at 8 and comprises a single strand of relatively stiff wire which, as seen in Figure 4 of the drawing, is first bent to substantially U-shape to define tines 9 and 10, the distance between the 10 tines being the equivalent of the distance between the openings 6 and 7 so that said tines may be readily inserted in the openings and passed through said openings to extend clear of the opposite side of the body of the brush for a 15 suitable distance. The portions of the tines which extend clear of the body are then twisted together throughout the major portion of their lengths as tightly as possible so that the resulting twisted portion will define a shank 11 which will 20 be relatively stiff. Moreover, the entire brush holder will be firmly and securely anchored in the body of the brush.

After the tines have been bent to define the shank 11, as above described, the shank is bent 25 medially of its length, at 12, to define an outer end portion or bill 13 which is disposed at substantially right angles to the inner portion of said shank. The outer portion 13 will, of course, normally be disposed in substantially parallel 30 spaced relation to the confronting wall of the brush.

As seen in Figures 1 and 3 of the drawing, when the brush is not in immediate use and it is desired to place it in a location where it will be 35 handy and yet not soil a surface or come in contact with soiled surfaces, the brush is placed in a bucket, indicated fragmentarily at 14, and the brush holder is engaged with the bill 13 thereof over the bead 15 of the bucket. It will be seen 40 that, in this position, the brush holder will effectively retain the brush against downward displacement in the bucket and will also locate the brush in a position handy for immediate use.

In view of the fact that the brush holder is 45 located intermediate the width of the body of the brush, as clearly seen in Figures 2 and 3 of the drawing, said brush holder will cooperate with the corners of the brush which confront the inner wall of the bucket for preventing wobbling of the brush in the bucket. It should be understood that the inner portion of the shank 11 is of sufficient length to permit ready engagement of the bill 13 of the holder over the 50 55

usual circular wall of a bucket without interference from the corners of the brush.

Attention is particularly directed to the fact that by locating the brush holder in the position indicated, it will not interfere with the proper holding of the brush in the hand of the user. Attention is also directed to the fact that inasmuch as the shank of the brush holder is formed of twisted tines which are bent to form the bill 13, an extremely rigid and simple holder is provided.

Referring now to the modification of my invention as seen in Figure 5 of the drawing, the numeral 16 indicates a portion of the body of a handle which is of similar construction to the handle 1. Formed in the portion 16 medially of its width is a groove 17 and mounted in the groove is a pin 18. In this embodiment, the brush holder is shown generally at 19 and said brush holder is formed in an identical manner as that of the preferred embodiment of the holder shown at 8. The holder 19 includes a bight portion 20 which passes over the pin 18 and has its ends confronting openings 21 in the handle portion 16. The pin 18, in the groove 17, will serve to provide reinforcement for the rear wall of the handle so that when the brush holder is being mounted in position and the tines are

being twisted to form the shank and hook, said bight portion 20 will not be drawn too deeply into the material of the handle. In case the material of the handle is soft, unless the pin 18 is employed, the bight portion might be drawn through or very deeply into the material of the handle, thus weakening the mounting of the brush holder in the handle as well as weakening the handle. Aside from the structure above described, the modification of the invention is identical with that of the preferred form and functions in a like manner.

Having thus described the invention, what I claim is:

In a device of the class described, a brush having a handle formed with parallel openings, and a brush holder comprising a single strand of wire bent to U-shape and defining tines projecting through the openings and clear of the brush, said tines being twisted together to form a shank with a portion thereof in contact with the handle between the openings, said shank projecting away from the face of the brush at substantially right angles thereto and being bent to form a hook having a bill located in parallel spaced relation to the face of the handle for supporting the brush on a support.

WINFRED W. DORSEY.
